United States Patent

Des. 238,891

Patented Feb. 17, 1976

238,891

MARBLE RUNWAY

James Walton Smith, 20 Martindale,
Greenwich, Conn. 06830

Filed Oct. 3, 1973, Ser. No. 403,226

Term of patent 14 years

Int. Cl. D21—01
U.S. Cl. D34—15 K

Fig. 1

Fig. 2

Fig. 3

FIG. 1 is a top plan view of a marble runway showing my new design;

FIG. 2 is a side elevational view thereof; and

FIG. 3 is a bottom plan view thereof.

I claim:

The ornamental design for a marble runway, as shown.
